COOLING BED ACTUATING MECHANISM

Roger Kinnicutt, Jr., Worcester, Mass., assignor to Morgan Construction Company, Worcester, Mass., a corporation of Massachusetts

Application March 26, 1952, Serial No. 278,689

2 Claims. (Cl. 74—44)

This invention relates to cooling bed mechanisms and more particularly to apparatus for actuating the packing arms of a cooling bed.

The cooling of bars and the like as they issue from a rolling mill is often done on a cooling bed having a series of notched members extending transversely of the bars. Some of these members are fixed and serve to support the bars, while the others are movable and serve to transfer the bars from one notch to another in the fixed members. One method of operation of such a cooling bed that has met with considerable success is called the "pack annealing" method. This involves assembling a considerable number of bars in stacked relation and moving them as a unit across the bed from notch to notch, this serving to prevent sudden cooling with its attendant disadvantages. In order to carry on this method of operation, it is necessary to transfer each bar from the runout table to the first notch of the fixed bars by means of a kick-off mechanism; then, the bars are stacked in the second notch by use of a packing arm which moves upwardly under each bar lying in the first notch and lifts it upwardly and forwardly. When the bar reaches a position over the second notch, the surface of the packing arm is inclined in such a manner that the bar slides off into the notch. It has been discovered that the optimum transfer of bars takes place when the packing arm moves upwardly and forwardly at a fairly constant velocity, stops over the second notch and remains there momentarily while the bar slides off, and then returns to its initial position. This motion prevents the bar from leaving the packing arm and pursuing an uncontrollable path of flight before landing in the second notch. The inclination of the surface of the packing arm and the stopping of the packing arm serve to make the component of weight of the bar parallel to the surface greater than the friction forces and the bar slides off. If the path of the packing arm is selected properly, the bar will slide off in the desired position in the notch, for instance, on top of the stack of preceding bars. However, previous mechanisms for producing such a motion for the packing arm have not been readily adaptable to conditions in a rolling mill. The mechanism is called upon to exert fairly large forces and must be quite rugged. Generally speaking, the mechanism will be situated under the cooling bed and will be subjected to the action of scale, dirt, and water. The present invention satisfies in a novel manner the needs for a mechanism which will function under those conditions.

It is therefore an outstanding object of the present invention to provide a mechanism for producing the optimum motion in the packing arms of a cooling bed.

Another object of this invention is the provision of an actuating mechanism for the packing arms of a cooling bed, which mechanism is capable of exerting large forces and resisting considerable shock loads.

It is a further object of the invention to provide a mechanism for producing a cycle of rectilinear motion having a first phase of constant velocity motion, followed by a

2

considerable period of zero velocity motion, after which the movement takes place back to the point of origin.

A still further object of the instant invention is the provision of a mechanism for producing a cycle of motion of the packing arm of a cooling bed, said cycle involving a movement upwardly and forwardly at a constant velocity, a pause for a considerable period of time, and a movement to the point of origin.

Although the novel features which are characteristic of this invention will be particularly pointed out in the claims appended hereto, the invention itself, as to its objects and advantages, the mode of its operation and the manner of its organization will be better understood by referring to the following description taken in connection with the accompanying drawings forming a part thereof, in which:

Figure 1 is a top view of an apparatus embodying the present invention.

Figure 2 is a sectional, somewhat enlarged, view of the apparatus taken on the line 2—2 of Figure 1.

Figure 3 is an elevation view of the apparatus with portions broken away taken on the line 3—3 of Figure 2, and

Figure 4 is an elevational view of the apparatus, partly sectioned, taken on the line 4—4 of Figure 2.

Referring first to Figure 1, wherein are shown the general aspects of the invention, the cooling bed mechanism, generally designated by the reference character 10, comprises a motor 11, a speed reducer 12, a gear box 13, and a motion converter 14. The motor 11, which may be any one of several types, but which preferably is capable of speed control, is connected through a coupling 15 to the speed reducer 12. The speed reducer may be any one of several well-known types having the function of receiving power on its input shaft at a given speed and driving apparatus connected to its output shaft at a considerably reduced rate of rotation. The reducer is connected through a coupling 16 to the gear box 13. The gear box 13 has two parallel, driven output shafts 17 and 18 which emerge from the opposite side of the box from an input shaft and which are spaced vertically from one another. The shafts 17 and 18 are provided with similar cranks 19 and 20, respectively, which are keyed to and rotate with their respective shafts. The outer ends of the cranks 19 and 20 are pivotally connected through similar connecting rods 21 and 22, respectively, to a yoke 23. The outer ends of the yoke 23 are pivotally connected to the connecting rods and the center portion is pivotally connected to a slide 24 which moves with reciprocatory motion only within the motion converter 14. The slide 24 is pivotally connected to a drive shaft 25 which extends horizontally from the converter. The drive shaft is connected through various bars and levers, not shown, to the packing arm of the cooling bed, also not shown. This latter connection is such that the packing arm partakes of a motion similar to that enjoyed by the drive shaft 25.

Referring next to Figure 2, wherein is shown the specific structure of the motion converter 14, it can be seen that the yoke 23, the connecting rods 21 and 22, and the cranks 19 and 20 move in planes perpendicular to the shafts 17 and 18 to which they are attached and by which means they are driven. The yoke 23 is pivotally mounted on a journal 26 which is a part of the slide 24. Generally speaking, the slide 24 consists of two side members 27 and 28 spaced from each other and joined by a forward crossbar 29, a rearward cross bar 30, and the journal 26. A journal member 31 is provided at the forward portion of the slide and it is on this journal that the drive shaft 25 is pivotally mounted. Referring next to Figure 4, the slide 24 is supported in a main housing 32 having opposite, spaced, upstanding walls 33 and 34 having guide members 35 and 36, respectively mounted on their opposed upper portions. The guide members

extend horizontally throughout the length of the main housing 32 and are formed externally with a dove-tail section which mates with a similarly shaped groove in the walls 33 and 34. They are fixed in the housing and held in position by means of clamps 37 and 38 which are suitably bolted to the walls 33 and 34, respectively. The sliding surfaces of the side members 27 and 28 and the guide members 35 and 36 are of a rectangular sectional conformation suitably relieved for lubrication. From this view of the apparatus it can be seen that the yoke 23 consists of a main hub rotatably mounted on the journal 26 having arms 39 extending in opposite directions adjacent each of the ends of the main hub. Each arm 39 has a hub 40 at its outer end in which is mounted a journal 41. Each journal 41 bridges its hubs 40 and has one of the connecting rods 21 and 22 rotatably mounted thereon between the hubs.

Referring next to Figure 3, wherein its best shown the structural details of the gear box 13, the shafts 17 and 18 are mounted in a housing 42 having a removable cover 43. Bearing members 44 are mounted in one side of the housing for supporting the crank end of the shafts, while bearing members 45 are mounted in the other side of the housing for supporting the other end of the shafts. Suitable seals and associated equipment are provided for each bearing. Keyed to the shafts 17 and 18 and movable therewith are similar gears 46 and 47 respectively. These gears are spaced vertically with respect to each other and both mesh with a pinion gear 48 keyed to the input shaft of the gear box.

The operation of the mechanism will now be evident from the above description. The motor 11 will be driven at a speed determined by the desired rate of operation of the packing arms of the cooling bed. The motor speed will be considerably reduced in the reducer 12 whose output shaft is connected to the input shaft of the gear box 13. The pinion gear 48 is keyed to the input shaft and drives the gears 46 and 47 in the same direction at the same speed of rotation. This means that the shafts 17 and 18 move in the same direction of rotation and at the same speed. The cranks 19 and 20 are thus driven together in the same direction and at the same speed; it is to be realized, however, that the outer ends of the cranks, which ends are pivotally attached to the connecting rods 21 and 22, reside in points which are symmetrical to the center line of the drive shaft 25 only once in a revolution. As a matter of fact, the ends of the cranks at any given moment are at points which are not only on opposite sides of lines drawn through the centers of their crank circles parallel to the drive shaft 25, but are also on opposite sides of a line joining the centers of their crank circles. This causes the center of the yoke 23 to move in a cycle of motion which is made up of a first phase of constant velocity motion in the forward direction, followed by a phase of zero velocity for an appreciable period of time, which is then followed by a phase of constant velocity rearward motion back to the point of origin. It is to be understood that the transition between phases may involve a short period of exponential or harmonic motion, but these are reduced to a minimum by the present device. The slide 24, of course, partakes of the motion of the center of the yoke and so does the drive shaft 25. Ultimately, the pack arm moves in a cycle of motion similar to that of the center of the yoke.

While certain novel features of the invention have been shown and described and are pointed out in the annexed claims, it must be understood that various omissions, substitutions, and changes in the forms and details 5 of the device illustrated and in its operation may be made by those skilled in the art without departing from the essence of the invention.

The invention having thus been described, what is claimed as new and desired to secure by Letters 10 Patent is:

1. In a rolling mill having a cooling bed with packing arms, a mechanism for actuating said packing arms, comprising: a gear box having an input shaft connected to a source of power, said gear box having two parallel, vertically-spaced, output shafts driven in the same direction of rotation and at the same speed, a crank fixed at one end to each of the output shafts of the gear box and rotating therewith in planes perpendicular to the axes thereof, a motion converter housing, guides mounted in 15 said housing, a slide mounted in said guides for reciprocatory motion in a line parallel to the plane of crank motion and lying between the center lines of the output shafts, a yoke mounted on said slide on a pivotal axis passing through its center and parallel to the center-lines of the output shafts, said yoke extending in opposite direction away from the slide, connecting rods each attached at one end to a free end of the yoke and at the other end to the free end of a crank, and a drive shaft 20 connected to said slide for imparting the motion thereof to the packing arms.
2. A mechanism for actuating the packing arm of a cooling bed, comprising: two parallel, vertically spaced shafts, a gear fixedly mounted on each shaft, a pinion gear meshing with the shaft gears and being driven from 25 a source of power, the shafts being caused to rotate in the same direction and at the same speed, a crank fixed to each of the shafts and rotatable therewith, a slide mounted for reciprocatory motion only in a line perpendicular to the axes of the shafts and lying there- 30 between, a yoke mounted on said slide for rotation about a line passing through the central portion of the yoke, said line being parallel to the axes of the shafts, two connecting rods pivotally attached at one end to an end portion of the yoke and at the other end to the free end 35 of a crank, the axes of pivotal attachment of the connecting rods to the yoke and the cranks being parallel to the shaft axes, and a drive shaft connected to said slide for movement therewith, the distances from the axes of the shafts to the axes of pivotal attachment of 40 the connecting rod to the free end of the respective crank arms being equal.
3. A mechanism for actuating the packing arm of a cooling bed, comprising: two parallel, vertically spaced shafts, a gear fixedly mounted on each shaft, a pinion gear meshing with the shaft gears and being driven from 45 a source of power, the shafts being caused to rotate in the same direction and at the same speed, a crank fixed to each of the shafts and rotatable therewith, a slide mounted for reciprocatory motion only in a line perpendicular to the axes of the shafts and lying there- 50 between, a yoke mounted on said slide for rotation about a line passing through the central portion of the yoke, said line being parallel to the axes of the shafts, two connecting rods pivotally attached at one end to an end portion of the yoke and at the other end to the free end of a crank, the axes of pivotal attachment of the connecting rods to the yoke and the cranks being parallel to the shaft axes, and a drive shaft connected to said slide for movement therewith, the distances from the axes of the shafts to the axes of pivotal attachment of the connecting rod to the free end of the respective crank arms being equal.
